John B. Osier

United States Patent Office.

JOHN B. OSIER, OF OGDENSBURG, NEW YORK.

Letters Patent No. 78,319, dated May 26, 1868.

IMPROVEMENT IN DEVICE FOR CUTTING SHEET IRON.

The Schedule referred to in these Letters Patent and making part of the same.

TO ALL WHOM IT MAY CONCERN:

Be it known that I, JOHN B. OSIER, of Ogdensburg, in the county of St. Lawrence, and State of New York, have invented a new and improved Mode of Cutting Sheet Iron and Tin; and I do hereby declare that the following is a full and exact description thereof, reference being had to the accompanying drawings, and to the letters of reference marked thereon.

The nature of my invention consists in providing two rectangular frames A A, attached to each other at B B, one with an inclined plane on the top, for the better facilitating the knives in cutting. On one frame are attached two perpendicular guides, C, at the corners of frame, at one end, and across is attached a cross-bar, that rises and falls on the guides; and on said bar are bolted knives with the edge being angular; and, in pressing the foot upon the treadle I, the knives are forced downwards; and, in passing by the knife on the other frame, at E, the edge being straight, the knife commences to cut at each outside edge of the sheet to be cut, and finishes at the middle of the knife.

To enable others skilled in the art to make and use my invention, I will proceed to describe its construction and operation.

I construct two rectangular frames A A, of sufficient size and width, supported on legs at the requisite height, and attached to each other at B B. On the top of one frame is an inclined top, and on the other is a level top of equal height. On one of the level tops, at the corners, are attached two perpendicular guides, C C, on which is attached a cross-bar, D, on which are bolted knives, the edge being angular, the edge at each end being lower, and in its downward motion the outside of the sheet commences to cut first, and finishes on the middle of the knife. On the end of the frame with the inclined plane on top, is attached a cross-bar, E. At each end of bar are attached three bolts, to move the knife at its proper distance, so as to let one knife pass close to each other in its motion. On the bar E is attached a knife, with the edge straight. On the top of the inclined plane is a sliding guide, F, and at each side of the top are marked the feet and inches, so as to set the guide at any desirable distance, thus enabling the operator to cut any desired width. On the top of the perpendicular guides is attached a cross-bar, G, on the top of which is attached a spring, H, and through the spring in the middle, is attached a rod that passes through and attached to cross-bar D, and through the cross-bar G, thus keeping the cross-bar D held up at sufficient height to allow the sheet iron or tin to pass through from one frame to the other on the top of the inclined plane to be cut. I is a treadle, attached under frame A, and J is a cross-bar, attached at each end by rods K K, and attached to cross-bar D, and passes between each frame at the middle, and attached to treadle I by a rod. The operator, in pressing his foot upon the treadle I, is enabled to force down the cross-bar D, and in passing the cross-bar E, with the knife attached, is enabled to cut sheet iron and tin, as desired.

What I claim as my improvement, and desire to secure by Letters Patent, is—

The construction and arrangement of the frames A A with the perpendicular guides C C, angular knife, and cross-bars D and E, with the spring H, and sliding guide F, and treadle I, all arranged and connected for the purpose set forth.

J. B. OSIER.
